UNITED STATES PATENT OFFICE.

JOHN THOMPSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

HARNESS STOP MECHANISM.

Application filed December 10, 1924. Serial No. 755,026.

This invention relates to improvements in mechanisms for stopping looms when a fault occurs in the harness operating connections and the general object of the invention is to stop the loom whenever the connections for the harness frames become broken or unduly slack.

Another object of my invention is to equip a loom having a closed ring of connections for operating the harness frame with devices operative to stop the loom whenever a break occurs at any point in the closed ring.

A still further object of the invention is to provide the center stop motion found in certain types of looms with auxiliary mechanism to stop the loom whenever the harness connections break.

With these and other objects in view which will appear as the description proceeds, my invention resides in the combination and arrangement of parts hereinafter described and set forth in the claims.

In the accompanying drawings, wherein I have shown a preferred form of my invention,

Fig. 1 is a rear elevation of a loom having my invention applied thereto,

Fig. 2 is a section taken on line 2—2 of Fig. 1, on an enlarged scale, certain parts of the loom being omitted,

Fig. 3 is a horizontal section taken on line 3—3 of Fig. 2, and

Fig. 4 is a fragmentary top plan view looking in the direction of arrow 4, Fig. 2.

Referring more particularly to the drawings it will be seen that I have provided a loom frame 10 having arches 11 provided with a gang of sheaves as at 12 adjacent the driving end of the loom and a second gang of sheaves 13 adjacent the head end of the loom, said sheaves being rotatably mounted on pins 14. Each harness frame 15 is provided with hooks 16 on the upper and lower rails thereof, the upper hooks being connected to straps or connectors 17 which pass over the sheaves 12 and 13 and are connected as at 18 to the upper arm 19 of a harness jack 20. Said jack 20 is pivoted as at 21 and has a lower substantially horizontal arm 22 which is connected as at 23 to a wire 24 the lower end of which is hooked and connected to a strap 25. Said strap passes around sheave 26 and extends horizontally,

having connection with a wire 27 the inner end of which is connected to strap 28 passing under sheave 29. The other end of the strap is attached by connections 30 to a yoke 31 which is connected to lower hooks 16. It is to be understood that the loom is provided with a multiple of the motions just described, there being a plurality of harness frames, each of which is provided with its own connections and harness jacks. The matter thus far described is of the usual construction and presents the positive harness motion common to the so-called Knowles loom.

My invention relates more specifically to the mechanism for stopping the loom should any of the connections for the harness frame become unduly slack or broken. Mounted in fixed position under the loom is a pair of spaced bearings 40 between which extend a shaft 41 having fixed at an intermediate point thereof a detector lever 42 which as shown in Fig. 2 extends horizontally under wires 27. Secured to the inner end of shaft 31 is an arm 43 which extends downwardly and has connection at the lower end thereof with a wire connector 44 the upper end of which is connected as at 45 to an auxiliary lever 46. Said auxiliary lever, as indicated in Fig. 4, is mounted on stud 47 extending laterally from stand 48 which is secured to the breast beam 49 of the loom and forms part of a well-known center filling stop motion. A collar 50 is adjustably mounted on said stud 47 and receives the end of a spring 51 the other end of which passes into the hub 52 of the auxiliary lever. Arm 53 of lever 46 is normally held to the right as shown in Fig. 2 by the spring 51, said spring serving also through the wire link 44 to hold the detector lever 42 in raised position.

Secured to the stand 48 is an inclined guide 54 over which extends a dagger 55. Said dagger is adjustably secured in a holder 56 pivotally mounted as at 57 to a stand 58 which is fastened to the lay 59. Pivotally connected at the upper part of the stand 58 is a lever 60 having connection with the tines 61 of the stop motion detector. A link 62 extends between the lever 60 and the holder 56 and whenever filling is present under the tines 61 said dagger 55 will be held in raised position as the lay moves forward. The normal position of the auxiliary lever is such

that under the conditions just described the upper arm 53 thereof will lie under the dagger 55 and said dagger will pass beyond the auxiliary lever without actuating the same.

5 A shipper shaft 63 is rotatably mounted in the loom frame in any approved manner and has secured thereto an arm 64 extending rearwardly and in proximity with the auxiliary knock-off lever. The usual knock-off lever for this type of motion is indicated at 65 and is pivoted on stud 47 and provided with a laterally extending boss 66 which extends over the arm 64. Said boss 66 also extends in front of the arm 53 so as to be engaged thereby when the same is moved forwardly. Depression of lever 64 will cause a motion of shaft 63 to stop the loom by well known mechanism not shown.

10 Under normal conditions with the harness lever intact the auxiliary lever will be held to the right as shown in Fig. 2, the detector lever 42 being in raised position. When any part of the harness connections become slack or broken the wire 27 corresponding to the defective connections or harness frame will be lowered, and by its weight will depress detector lever 42. The weight of each wire 27 is sufficient to overpower the spring 51 and when said lever 42 is depressed the end 30 53 of the auxiliary knock-off lever will be moved to the dotted line position shown in Fig. 2 in the path of the dagger 55 as the latter moves forwardly upon engagement of the arm 53 with the dagger 55 said arm will move forwardly against boss 66 causing the latter to be depressed to move arm 64 and the shipper shaft 63 to stop the loom. It is to be understood that the arm 53 will project sufficiently above the stand 48 and lever 65 35 to be engaged by the dagger 55 when the latter is held in elevated position by weft under the tines 61.

40 From the foregoing it will be seen that I have provided a loom having a closed ring 45 of connections to actuate the harness frames positively in both directions, combining the same with a stop motion having a detecting

member under the lowest part of the connections and effective upon a fault in any part of the connections to stop the loom 50 through the filling stop motion. Many of the motions heretofore proposed for stopping the loom when a faulty connection for the harness frame occurs have depended for their operation upon the downward motion of the frame but the motion shown herein will be operative to stop the loom when a defect occurs at any point in the closed ring of connections. Thus, should the connection 23 become defective or the lower arm 22 of the 55 harness jack become broken or the strap 25 be disengaged from either of the wires 24 or 27 or should a fault occur in yoke 31 or any of the connections between the same and the wire 27, the latter will fall even though 60 the harness frame be supported by arm 19.

Having thus described my invention it will be apparent that changes and modifications may be made therein by those skilled in the art without departing from the spirit 70 and scope of the invention, and I do not wish to be limited to the details herein disclosed but what I claim is:

75 In a harness stop mechanism for a loom having a lay, a harness lever, a harness frame, connections from the harness lever to the top of the frame, and other connections from the harness lever to the bottom of the frame, said other connections including a metallic portion relatively heavier than the 80 remainder of said other connection, a dagger mounted on the lay and movable relatively thereto, a knock-off lever mounted on a fixed pivot and normally out of the path of the dagger, a yielding lever located under the 85 metallic portion of said other connections, and means connecting said yielding lever and the knock-off lever to move the latter into the path of the dagger when the metallic portions of connections fall and depress the yielding lever.

90 In testimony whereof I have hereunto affixed my signature.

JOHN THOMPSON.
